UNITED STATES PATENT OFFICE

OSCAR A. BOSS, OF NEW YORK, N. Y.

CIRCUIT BREAKER

Application filed December 2, 1930. Serial No. 499,429.

This invention refers to circuit closers and more particularly to that class wherein a movable contact supporting member is arranged to contact with a fixed contact member.

This invention comprises a modification of the invention disclosed in my co-pending application Serial No. 298,447, filed August 9, 1929 of which this instrument forms a continuation in part.

In the adjustment of contacts employed in circuit closers, as for example, the circuit breaker employed in internal combustion motor ignition apparatus, the contacting faces of the contacting portions become misaligned owing to the circuit breaker being pivotally supported, the pivoted contact moving through an arc of a circle and the stationary contact moving in a lineal plane as said contacts are adjusted. The usual practice is to bend the support of the fixed contact until the contacting surfaces appear to be parallel, however true parallelism can rarely be obtained in this manner and as a result of which the contacts bear at only one point of the contacting surfaces thereof.

The applicant has conceived a novel form of supporting a contact member whereby the contacting faces of the mating contacts may be quickly self-aligned without the bending or deformation of the contact supports, also producing a contact support of a form whereby the contact will be automatically self-aligned during the contacting operation thereof.

Another accomplishment comprises the furnishing of a contact supporting device wherein the tension tending to seat the contact is in the direction of making contact, whereby the contact is positively moved as the contact support is actuated to open the circuit irrespective of the vacuum which may be caused between the contacting faces due to high speed of operation and perfect parallelism of said contacting faces.

Another accomplishment comprises furnishing a self-aligning contact member wherein the movement thereof for alignment with the mating contact associated therewith, is accomplished without any rela-

tive movement with respect to the resilient member constraining said contact member to its seat or with respect to the movement of the contact supporting member.

Another accomplishment comprises in furnishing a circuit breaker wherein the contact member may be quickly replaced without removing the circuit breaker from its support and without adding appreciable weight to the movable end of said breaker. Other objects and advantages will appear as the description of the invention progresses, and the novel features of the invention will be pointed out in the appended claims.

This invention consists in the novel construction and arrangement of parts hereinafter described, delineated in the accompanying drawing, and particularly pointed out in that portion of the instrument wherein patentable novelty is claimed for certain and peculiar features of the invention, it being understood that, within, the scope of what hereinafter thus is claimed, divers changes in the form, proportions, size and minor details of the device may be made without departing from the spirit of, or sacrificing any of the details of the invention.

In describing the invention in detail reference is had to the accompanying drawing wherein I have illustrated embodiments of my invention, and wherein like characters of reference designate corresponding parts through the several views, and in which:

Figure 1 is an enlarged part sectional view of a circuit breaker to which applicant's invention has been applied, and Fig. 2 is a plan view of the same taken on line 2-2 of Fig. 1, and Fig. 3 is an end elevational view of the same taken on line 3-3 of Fig. 1, and Fig. 4 is a perspective view of a circuit breaker illustrating the method of replacing contacts thereinto.

Referring to Figs. 1, 2 and 3, the circuit breaker arm 1 which may be of the general form of circuit breaker now employed in connection with ignition systems for internal combustion motors, has a contact supporting portion 2 formed at one end thereof, in which is preferably stamped a concave recess or seat portion 3, having seat 4 and orifice 5,

through which is arranged to be inserted the contact portion 7 of contact member 6, said contact member having a convex seat portion 8 formed with seating surface 9 arranged to 5 impinge onto seat 4. Contact member 6 is also formed with allocating projection 10 having an apex 10a arranged to receive impingement of the free end 11 of spring or resilient member 12, the rotating end 13 of 10 which is rotatively secured to arm 1 by tubular rivet 14, said spring member having a depression 15 arranged to seat in groove 16 formed in said arm.

The distance A between the apex 10a of 15 projection 10 and the free end 11 of spring 12, and the seating surface 9 of seating portion 8 is substantially equal to the radius of the arc forming said seating surface whereby as contact member 6 is rotated in seat 4 of 20 seating portion 3, no movement occurs between said apex 10a and the free end 11 of spring 12.

The projection 15 of spring 12 is normally seated in groove 16 to prevent the free end 25 11 thereof from accidentally leaving the apex 10a. However, when it is desired to replace a contact as 6, the free end 11 is constrained sidewise as shown by Fig. 4 and whereafter the old contact member 6 may be removed and 30 a new one inserted in the place thereof.

The tension of the free end 11 of spring 12 is preferably sufficient whereby the contact member 6 will not align from normal 35 pressure of the breaker arm spring (not shown) during the inoperation thereof, however by depressing the contact supporting portion 2 toward the stationary contact with which contact member is arranged to contactingly engage, whereby the contacting face 7b of contact portion 7a will be aligned with said stationary contact, the seating portion 8 of said contact member rotating in seat 4 without effecting any movement between the apex 10a and the free end 11 of spring 40 12. If when replacing the contact member 6, said member is not aligned as described, due to inadvertence, the hammering action of the contacts during the making and breaking of the circuit controlled thereby will, in 45 a comparatively short space of time, automatically act to cause alignment thereof by constraining frictional movement between the seating faces 4 and 9 as said hammering action takes place.

50 The free end 11 of spring 12 is preferably formed to have a tension whereby the seating surfaces 4 and 9 will remain continually in contact irrespective of the speed at which the circuit breaker is being operated during the opening and closing of the circuit with which it may be associated.

55 It is to be noted that the contact member 6 is inserted through orifice 5 from the top side of the contact supporting portion 2 for seating the seating face 9 onto seating face

4 of said portion, and that said seating surfaces are so arranged that when the contact face 7b is separated from the fixed contact with which it engages, said contact member 6 is positively moved away from said fixed contact thereby preventing any change in timing of the ignition circuit controlled thereby.

What I claim is:—

1. A circuit breaking device comprising, a 75 contact supporting member having an opening formed therein between the forward and rearward sides thereof, a rearwardly facing seat formed on the rearward side of the member surrounding the opening therein, a resilient member supported by the contact supporting member having an extension positioned spaced rearwardly of the seat therein, a self-aligning contact member having a seating portion and a contacting portion, the seating portion having a forwardly facing convex seating surface arranged to frictionally engage the rearwardly facing seat on the contact supporting member and the contacting portion extending forwardly from the seating portion spaced through the opening beyond the forward end thereof, a rearwardly protruding extension formed on the seating portion rearwardly of the seating surface thereon, the end of the extension engaging 90 the extension of the resilient member and the point of engagement of the extensions forming substantially the nucleus from which the arc of the seating surface on the seating portion of the self-aligning contact member is generated.

2. A circuit breaker comprising, a trough shaped breaker arm, a sleeve member secured to the side walls of the arm adjacent one end thereof for pivotally supporting the breaker, an opening formed in the bottom wall of the arm adjacent the free end thereof, a seating portion formed in the bottom wall of the arm surrounding the opening therein, the seating portion having a seating surface facing outwardly with respect to the bottom wall of the arm, a self-aligning contact member having a seating portion and a contacting portion, the seating portion engaging the seating surface of the arm seat portion and the contacting portion extending spacedly through the opening into the trough of the arm, a contacting face formed on the end of the contacting portion extending into the trough of the arm, arranged to engage a 105 contacting face of a correlated contact member, and means supported by the breaker arm for resiliently urging the contacting portion of the self-aligning contact member to frictionally engage the seating surface on 110 the seating portion of the arm.

3. A circuit breaker comprising, a breaker arm having a seat formed thereon, a self-aligning contact member having a seating portion and a contacting portion, the seating

- portion frictionally engaging the arm seat and the contacting portion being supported by the seating portion independently of the breaker arm, and a resilient member having one end thereof pivotally supported by the arm and the free end thereof arranged to normally engage and urge the contact member to its seated position when the resilient member is positioned in the normal pivoted position thereof and will permit the removal of the contact member from the arm for replacement thereof when the resilient member is positioned in another pivoted position, the axis of the pivoted end of the resilient member and the axis of the arm seat being spaced on the arm one from the other.
4. A circuit breaker comprising, a breaker arm having a seat formed thereon, a self-aligning contact member having a seating portion and a contacting portion, a seating portion frictionally engaging the arm seat and the contacting portion being supported by the seating portion independently of the breaker arm body, a resilient member having one end thereof pivotally supported by the arm and the free end thereof arranged to engage and urge the contact member to its seated position when the resilient member is positioned in the normal pivoted position thereof and will permit the removal of the contact member from the arm for replacement thereof when the resilient member is positioned in another pivoted position, the axis of the pivoted end of the resilient member and the axis of the arm seat being spaced on the arm one from the other longitudinally thereof, and means resiliently restraining pivotal movement of the resilient member from the normal position thereof.
5. A contact member for self-aligning circuit breakers comprising, a contacting portion having a substantially flat contacting face formed forwardly thereon, a seating portion formed on the member rearwardly of the contacting portion, the seating portion having a forwardly facing convex seating surface thereon arranged to frictionally engage a correlated seat for self-aligning the member, and a locating portion formed on the member rearwardly of the seating portion thereof, the locating portion having a rearwardly facing apex for seating the member, the apex forming substantially the nucleus from which the arc of the convex seating surface is generated.
6. A contact member for self-aligning circuit breakers comprising, a contacting portion having a substantially flat contacting face formed forwardly thereon, a seating portion formed on the member rearwardly of the contacting portion thereof, the seating portion having a forwardly facing convex seating surface thereon arranged to frictionally engage a correlated seating surface for self-aligning the member, a groove formed on the member positioned between the contacting portion and the seating portion, and a locating portion formed on the member rearwardly of the seating portion thereof, the locating portion having a rearwardly facing apex arranged to frictionally seat the member upon constraint of a resilient member thereagainst.
7. A circuit breaking device comprising, a breaker arm arranged to have one end thereof pivotally supported, a seat formed on the free end of the arm, a self-aligning contact member having a seating portion and a contacting portion, the seating portion frictionally engaging the arm seat and the contacting portion being supported by the seating portion independently of the arm body, a resilient member having one end thereof pivotally supported by the arm and the free end thereof resiliently urging the seating portion of the contact member to frictionally engage in the arm seat, the axis of the pivotally supported end of the resilient member being positioned spacedly between the pivotally supported end of the arm and the seat in the free end thereof.
8. A circuit breaker comprising, a contact supporting member having an opening formed between the forward and rearward sides thereof, a rearwardly facing seat formed on the rearward side of the supporting member surrounding the opening therethrough, a self-aligning contact member having a rearwardly seating portion, the seating portion having a forwardly facing seating surface arranged to frictionally engage the seat on the supporting member, a contacting portion formed on the self-aligning contact member extending forwardly from the seating portion spacedly through the opening beyond the forward end thereof, the contacting portion forwardly of the seating portion being insertable through the opening upon seating the seating surface of the seating portion onto the seat of the supporting member whereby the self-aligning contact member may be bodily removed from or seated in the contact supporting member, a contacting face formed on the forward end of the contacting portion arranged to contactingly engage a correlated contacting face, and means supported by the contact supporting member for resiliently urging the seating portion of the contact member to frictionally engage the seat in the supporting member.

In testimony whereof I hereby affix my signature.

OSCAR A. ROSS.
